UNITED STATES PATENT OFFICE

119,857

DESIGN FOR A CLIP PIN OR SIMILAR ARTICLE

Lester Hess, New York, N. Y., assignor to Nat Levy-Urie Mandle Corporation, New York, N. Y.

Application February 15, 1940, Serial No. 90,280

Term of patent 7 years

To all whom it may concern:

Be it known that I, Lester Hess, a citizen of the United States of America, residing in the city of New York, county of New York, and State of New York, have invented a new, original, and ornamental Design for a Clip Pin or Similar Article, of which the following is a specification, reference being had to the accompanying drawing, forming part thereof.

Fig. I is a front view of a clip pin or similar article showing my new design.

Fig. II is a side view thereof.

Fig. III is a rear view thereof.

I claim:

The ornamental design for a clip pin or similar article, substantially as shown.

LESTER HESS.
